UNITED STATES PATENT OFFICE.

BARTLEY O'LAUGHLIN, OF CORAL, MICHIGAN.

MAIL-BAG-CATCHING DEVICE.

1,267,109.

Specification of Letters Patent. Patented May 21, 1918.

Application filed May 11, 1915. Serial No. 27,395.

To all whom it may concern:

Be it known that I, BARTLEY O'LAUGHLIN, a citizen of the United States, residing at Coral, in the county of Montcalm and State 5 of Michigan, have invented certain new and useful Improvements in Mail-Bag-Catching Devices, of which the following is a specification.

This invention relates to a device for 10 catching mail bags delivered from cars in motion.

The object of this invention is to provide 15 a mail bag catching device that is so constructed as to receive a mail bag and so retain the same as to prevent its removal therefrom and also to receive the bag in such a manner as to efficiently absorb the shock incident to the impact of the same against the device.

20 A still further object of this invention is to provide a mail bag catching device, the same comprising a frame resiliently supported and pivoted to this frame is a pair of yieldably connected lids, the means for connecting the lids receiving the mail bag and the lids being turned over to efficiently retain the mail bag in engagement with the device.

25 A still further object of this invention relates in the provision of a device that is simple in construction, efficient in operation, and consists of a minimum number of parts.

With these and other objects in view, this 30 invention consists of certain novel constructions, combinations and arrangement of parts, as will be hereinafter fully described and claimed.

In the accompanying drawings:—

Figure 1 is a view in side elevation of the 40 improved device;

Fig. 2 is a top plan view;

Fig. 3 is a section taken on line 3—3 of

Fig. 2.

45 Referring to the parts by reference numerals, supporting standards are shown, the shorter of the same being designated by the numeral 10 and the longer by the numeral 11. The upper ends of the standards 10 are bifurcated forming grooves into which a portion of the coil springs 12 are positioned to prevent the lateral displacement of the same, these coil springs 12 are secured to the post 10 by means of the bolts 13. Coil springs 14 are carried by the higher standards 11 by means of the bolts 15, that pass therethrough, and as is clearly shown in

Fig. 1, the same are so disposed as to engage the mail bag catching device and retain that end which the same are connected with in substantially the same plane as the height of 60 the standards 10. The mail bag catcher comprises a rectangular frame 15, the same having secured adjacent its longitudinal sides, bars 16. Lids 17 are hingedly secured to the bars 16 by means of the eyes 18 embracing the said bars, the said lids having a netting 19 carried thereby and abutment portions 20 at certain ends thereof. A plurality of coil springs 21 are secured to the longitudinally extending portions 22 of the 70 lids 17 and as is clearly shown in Figs. 2 and 3, these coil springs span the frame when the device is in a position to receive a mail sack, the lids thereof being positioned against the longitudinal portions 23 of the 75 frame, the longitudinal portions thereof being positioned in a higher plane than the rods 16.

This device is placed adjacent the track and with the post 11 nearest thereto and is 80 normally in a position as shown in the accompanying drawings, however, when the mail sack is delivered on the coil springs 21, the weight of the sack will move the coil springs 21 downwardly between the rods 85 16 and thus move the lids 17 to a closed position or, in other words, until the abutments 20 engage the frame 15. The position that the device would then assume is indicated in Fig. 3. It will be seen that the 90 coil springs 18 will conform to the shape of the mail bag and the weight of the bag will retain the lids in a closed position with the abutments 21 resting on the frame 15. After the mail bag has been removed from the springs, the said springs will assume their normal position, that as shown in the accompanying drawings and the lids 17 will be moved so as to rest against the longitudinal portions of the frame 15.

95 It is obvious that minor changes may be made in the form and construction of this invention without departing from the material parts thereof. It is therefore not wished to confine the invention to the exact 105 form herein shown and described, but it is wished to include all such as properly come within the scope claimed.

100 What is claimed is:

1. In a mail bag catcher, a resiliently supported frame, a pair of lids hingedly secured to said frame, resilient means con-

necting said lids for receiving a mail sack whereby when a mail sack is placed thereon, said lids will be moved to a closed position to prevent the accidental removal of said 5 mail sack.

2. In a mail sack catching device, a resiliently supported frame provided with hingedly secured lids having abutments formed thereon and means connecting said 10 lids for receiving a mail sack whereby said lids are moved so as to bring said abutments in engagement with said frame and thus by the weight of the mail sack prevent the accidental removal of the mail sack.

15 3. In a mail sack engaging device, a frame resiliently supported, including a pair of longitudinal members, the longitudinal members of said frame being disposed in a higher plane than the remainder thereof, 20 bars carried by said frame, lids hingedly secured to said bars, means connecting said lids for normally retaining the same in en-

gagement with the longitudinal portions of said frame and providing means for the receiving of a mail sack whereby the sack by 25 its weight moves said lids to a closed position and prevents the accidental removal of the sack therefrom.

4. In a device for catching mail sacks, a frame, means for receiving a mail sack on 30 said frame, supporting standards, springs connecting said frame to said supporting standards and means independently of the securing means on certain of said supporting standards for the reception of said 35 springs to prevent the lateral displacement thereof.

In testimony whereof I affix my signature in presence of two witnesses.

BARTLEY O'LAUGHLIN.
